MEANS FOR VENTILATING ATTIC SPACES

Ernest O. Howle, Chicago, Ill.

Application April 19, 1943, Serial No. 483,678

3 Claims. (Cl. 98—46)

The present invention relates to means for ventilating attic spaces of buildings and is more particularly directed to use in connection with low-priced housing projects.

Recently there have been erected many low-priced housing projects so built that cost is reduced to a minimum, and efficiency and use to a maximum.

In order to afford adequate protection concerning temperature changes, it is the usual practice to insulate such buildings, and particularly the ceilings forming the floors of the attic spaces.

Experience has demonstrated that where attic spaces are not ventilated, the presence of the dead air deteriorates the ceiling insulation, thus impairing the ceilings of the buildings and at the same time reducing the heat insulation effect through the roof.

An object of the present invention is to provide a means for ventilating attic spaces in which the fire hazard is eliminated.

Another object of the invention is to provide means for insulating attic spaces, particularly in low-cost housing projects where maximum safety must be combined with minimum cost.

A further object of the invention is to provide ways and means for ventilating attic spaces to prevent deterioration of the insulating material used in the ceiling construction.

The above, other and further objects of the present invention will be apparent from the following description and accompanying drawing.

The accompanying drawing illustrates preferred features of the present invention and the views thereof are as follows:

Fig. 1 is a vertical sectional view through a chimney constructed of inner and outer pipes of metal, and a fragmental sectional view of a flat roof showing the manner of mounting the chimney with respect to the roof structure, and illustrating the ways and means of ventilating the attic space;

Fig. 2 is a fragmental view partially in section and partially in elevation, showing adaptation of the present invention to a building having a sloping roof;

Fig. 3 is a vertical sectional view taken through the center of the basket and showing details of construction; and

Fig. 4 is an isometric view of the insulating member which surrounds the flue pipe of the chimney where it passes through the ceiling and roof of the building.

The drawing will now be explained.

Referring to Fig. 1, 1 designates generally the

flat roof of a building. 2 represents the ceiling, which, with the roof 1, forms an attic space 3.

The chimney, as illustrated, includes a flue A and a surrounding casing B, the latter of which extends upwardly from the roof and terminates adjacent the upper end of the flue.

The flue A is composed of sections of vitrified enamel pipe which sections 4 have lower male end portions 5 and upper female end portions 6. Spaced upwardly from the lower ends of the sections are outwardly extending beads or flanges 7, so that when the sections are connected in nested relation, the bead 7 of one of the sections will rest on top of the upper margin of the female end 6 of the section next below it, and thus maintain the flue in stacked relationship.

There is a top section comprising a flue portion 8 which telescopically engages the upper end of the uppermost of the sections A. Welded or otherwise secured to this top section 8 is a casing 9 which is radially spaced from the portion 8, and which has a lower female or skirt portion 10 to engage over the upper end of the section next below it to provide a water-tight joint between the casing 9 and the portion B of the casing next below it.

A basket C is provided for supporting the flue section of the chimney and also for supporting the insulating member D which surrounds the flue in its passage through the ceiling 2, attic space 3, and roof 1.

The basket is provided with a bottom 11 which is centrally apertured at 12 to surround a flue section. The wall of the basket extends upwardly from the bottom 11 divergently, and near its top is formed with an outwardly extending bead or flange 13. At intervals along its inner curved surface, straps 14 are welded at 15 or otherwise attached to the basket. The upper ends of these straps may be secured to the roof, as shown in Fig. 1, or secured to the ceiling framework, as shown in Fig. 2. As illustrated, the basket is mounted in position to extend downwardly a short distance below the ceiling 2, into the room space through which the chimney passes. The bead or flange 13 of the basket C may be utilized to support the adjacent margins of the ceiling 2, as illustrated in Figs. 1 and 2. Flange 7 of the flue rests on the bottom of the basket to support the flue stack.

The casing B, as well as the portion 9 of the top section, are radially spaced from the flue A to form an air space 16 between the flue and the casing.

For insulating the flue where it passes through

the ceiling, attic space and roof, there is provided an insulating member D herein illustrated as a unitary structure of the proper diameter and length. The inner diameter of this member is greater than the outer diameter of the flue A, so that when in position in the basket, the air space 17 is provided between the flue and the member D. The member D is provided with notch means 18 in its lower margin, so as to provide air entrance to the air space from the space between the exterior of the member D and the inner surface of the basket C. The parts are so constructed and arranged that the air space 17 is in register with the air space 16.

For supporting the casing B on the roof, a roof plate E is used. This plate has a flange portion 19 extensive enough to overlie and cover the opening 20 in the roof through which the chimney passes. The roof plate E has an angularly flanged portion 21 which surrounds the upper end of the insulating member D. The casing B is welded or otherwise attached to this flange 21, thus making the casing B and the roof plate E a unitary structure.

In order that the air in the spaces 16 and 17 may escape to the atmosphere, and thus create circulation to withdraw air from the attic space 3, the portion 8 of the top section of the chimney is apertured at 22.

It is to be understood that, as optional construction, instead of forming the apertures 22 in the flue, similar apertures might be made in the casing portion 9 of the top section for venting the air of the atmosphere.

Referring to Fig. 1, it will be observed that air passageway is provided from the attic space 3 downwardly between the interior of the basket C and the exterior of the insulating member D, thence through the notch means 18 into the air space 17, upwardly through the air space 16, and to the atmosphere through the apertures 22.

During the winter time, when the building is being heated, the flow of the products of combustion through the flue A will cause sufficient draft in the air space to properly ventilate the attic space. During the summer time, when there is no heat, circulation will be created by reason of the fact that the air space 16 is in communication with the atmosphere, and to prevent mildew.

It is to be observed that in the present invention, the air escaping from the air space 16 to the atmosphere does so at a point far enough from the roof to eliminate any fire hazard, in the event that said escaping air should be hot enough to ignite combustible material in the roof.

Referring to Fig. 2, the roof 1a is inclined. A basket C is attached to the ceiling framing 23 by nailing or otherwise securing the straps 14 to the framing. The roof plate E' is made with its flange 19' at an angle to conform to the sloping of the roof. In this form of the invention, the insulating member D extends from the bottom 11 of the basket C, upwardly through the roof, where it is surrounded by the flange 21' of the roof plate E'.

The present invention has been illustrated and explained in connection with a chimney made of metallic sections. It is to be understood that the invention is applicable to any chimney construction in which an air space is provided about the chimney flue and in which communication is established between the attic

space and the air space. It is an important feature of the present invention that the vented air from the air space about the flue be delivered to the atmosphere far enough away from the roof so as to preclude any possibility of fire hazard.

The invention has been described herein more or less precisely as to details. It is to be understood that the invention is not to be limited thereby, as changes may be made in the arrangement and proportion of parts, and equivalents may be substituted without departing from the spirit and scope of the invention.

The invention is claimed as follows:

1. Means for ventilating attic spaces of a building having a roof and a ceiling defining the air space, a heater flue extending upwardly through the ceiling and roof, a casing about the flue between the roof and the upper end of the flue to provide an air space, the upper end of said casing being sealed to the flue, a roof plate apertured to encircle the flue and constitute the sole support for said casing, a basket supported to surround the flue and project below the ceiling and having an apertured bottom encircling the flue with the upper end of the basket opening into the attic space, said flue having an annular flange to rest on the bottom of said basket to support the flue in position, an annular insulating member surrounding the flue and resting on the bottom of said basket in spaced relation to the flue to provide an air space in communication with said first mentioned air space and with the exterior of the insulating member inwardly spaced from the basket wall, the length of said insulating member extending upwardly from the bottom of said basket through the ceiling and roof with its upper end terminating above the roof, the lower end of said insulating member having notch means in it, said roof plate having the portion thereof which is adjacent the flue upwardly offset to provide a pocket for the upper end of said insulating member, the construction being such that a path of air travel is provided from the attic space downwardly between the basket and insulating member through the notch means therein into the air space and thence upwardly and to the atmosphere adjacent the upper end of the flue, and means for the escape of air from the upper end of said air space to the atmosphere.

2. In a building construction, means for ventilating an attic space, in combination with a chimney, casing means surrounding the chimney flue in spaced relation thereto to provide an air space therebetween, a support for said casing means attached to the roof, a basket suspended from the ceiling framework about the flue and projecting below the ceiling with the upper end of the basket opening into the attic space between the roof and said ceiling, insulating material supported by said basket and surrounding the flue from a point below the ceiling to a point above the plane of the roof, said insulating material being spaced from the flue to provide an air space therebetween in communication with the air space between the flue and its casing and with the exterior of the insulating material inwardly spaced from the basket wall, means for air travel from the space between the insulating material and basket wall to the space between the insulating material and the flue, said basket having an apertured bottom through which the flue passes and which supports that portion of the flue above the basket bottom, said flue having a flange or

bead in engagement with the basket bottom, and means providing communication between said air space and the interior of the flue to create draft from the attic space through said air space and to the atmosphere.

3. In a building structure, an air space defined by an upper member as a roof and a lower member as a ceiling or floor, a flue projecting upwardly through said upper and lower members, casing means about said flue spaced from the flue to provide an air space therebetween, a roof plate connected to said casing means for supporting it, a basket hung from the lower member framework and projecting below said lower member with its upper end opening into said space, 15 the bottom of said basket member being aper-

tured to surround the flue, said flue being formed with a flange or bead for resting on the basket bottom to support the flue in position, insulating means extending along and surrounding said flue from a point below the lower member to a point above the upper member and resting on and supported by the basket bottom with an air space between the flue and the insulating means, the exterior of said insulating means being inwardly spaced from the basket wall, means providing an air passage from the space between the basket wall and insulating means to the air space within said casing, and means for venting the last mentioned air space to the atmosphere.

ERNEST O. HOWLE.
